(57) **CLAIM**

Ornamental designs for cutting insert for metal chip removal, as shown and described.

DESCRIPTION

FIG. 1 is a top, front perspective view of a cutting insert for metal chip removal showing a new design.

FIG. 2 is a top plan view thereof.

FIG. 3 is a left elevational view thereof.

FIG. 4 is a right elevational view thereof.

FIG. 5 is a front elevational view thereof.

FIG. 6 is a rear elevational view thereof; and,

FIG. 7 is a bottom plan view thereof.

The present design relates to cutting inserts for metal chip removal and, more particularly, to families of cutting inserts usable in the same toolholders, preferably in milling cutters. The broken lines in the drawings depict unclaimed environmental subject matter.
